UNITED STATES PATENT OFFICE

JOHN F. HOLZMAN, OF OLcott, NEW YORK
ILLUMINATING DEVICE

Application filed April 30, 1930. Serial No. 448,537.

This invention relates to improvements in illuminating devices, but more particularly to a lighting system for dance halls, theaters and other amusement places where it is desirable to produce variegated light displays. One of its objects is to provide a revolvable illuminating device of this character which has been designed to create a rolling or blending of the colored light rays one into the other, whereby a unique and variegated lighting effect is produced.

Another object of the invention is the production of a variegated lighting device which is simple, compact and inexpensive in construction, which is reliable in operation, and which requires a minimum amount of power to operate it.

In the accompanying drawings:—

Figure 1 is a side elevation of my novel illuminating device. Figure 2 is a top plan view thereof. Figure 3 is an enlarged vertical longitudinal section of the device.

Similar characters of reference indicate corresponding parts throughout the several views.

This improved illuminating device has been designed for suspending it overhead to throw the variegated light rays downwardly and outwardly onto the floor and around the side walls of a dance hall, stage or like amusement place. To this end, the lamp structure has been shown suspended from a ceiling 10 and includes a revolving, upright supporting post 11 journaled at its upper end in bearings 12, 12 applied to a suitable casing 13 secured to the ceiling. This post carries a source of light, such as an electric lamp 14, and a reflector 15 for directing the light rays radially outward. By preference, the reflector is supported in a substantially semi-circular yoke or member 16 interposed between the upper and lower ends of the post to turn therewith. The reflector is adjustable circumferentially of this yoke to vary the angle of the light rays, and for this purpose is provided with an adjusting screw 17 engaging a longitudinal slot 18 in the yoke, as shown in Figure 3. The lamp 14 also revolves with the post and is mounted on an arm 19 projecting radially therefrom. This post is preferably tubular in form and the current-conducting wires 20 leading from the lamp socket 21 pass upwardly through the hollow post and are electrically connected to collector rings or collars 22 secured to the upper end of the post and insulated from each other. The electric current from the supply source is conducted to the collector rings through the medium of contact strips 23 yieldingly engaging said collector rings.

Motion is transmitted to the post 11 by an electric motor 24 or other source of power, the latter being connected by a sprocket chain 25 with a sprocket wheel 26 mounted on a transverse shaft 27 which is also provided with a worm 28 meshing with a worm wheel 29 secured to a longitudinal shaft 30 supported at its outer end in a bearing bracket 31 and at its inner end in the adjoining wall of the casing 13. The inner end of said shaft 30 is provided with a bevel gear 32 meshing with a similar gear 33 secured to the upper end of the post 11. This train of gearing from the motor to the post is such that the lamp 14 and reflector 15 are revolved at a comparatively slow speed.

Surrounding the lamp and reflector to revolve relatively thereto is a lamp body consisting of an upper frusto-conical portion 34 preferably closed at its upper end by a disk 35 containing bearings 36 through which the upper end of the post 11 extends, and a lower portion of conical shape composed of a plurality of substantially triangular shaped, colored glasses or lenses 37. These lenses are firmly secured at their opposing upright edges between inner and outer supporting strips 38 suitably fastened at their upper ends to the base of the frusto-conical portion 34 and at their lower ends to a collar 39 applied to a thrust bearing 40 provided at the lower end of the post 11. The upper frusto-conical portion of the lamp body is preferably cylindrical in cross section and the lower conical portion is polygonal in cross section, the upper ends of the variegated lenses 37 being disposed within the marginal edge of such frusto-conical portion. The resulting gaps or segmental openings between these parts are preferably sealed or closed by hori-

- zontally disposed plates 41, as seen in Figure 3, and are welded or otherwise fastened to the upper portion of the lamp body. The inner wall or surface of the frusto-conical portion 34 of the lamp body is preferably highly finished or polished to form a reflecting surface, some of the lamp-rays being directed against this surface and then reflected therefrom through the lenses 37.
- 10 The lamp body 34, 37 is revolvable about the lamp 14 and its reflector 15 and preferably in the reverse direction and at a faster speed than that of these parts. Motion may be transmitted to the lamp body from the 15 shaft 30 by means of a friction wheel 42 applied thereto and engaging an annular track or surface 43 applied to the upper portion 34 of the lamp body, as shown in Figures 1 and 3.
- 20 By this construction and arrangement of parts, when the motor is started, motion is transmitted to the lamp 14 and reflector 15 in one direction and to the lamp body 34, 37 in the opposite direction and at different 25 relative speeds. This relative rotation of the parts results in a variegated display of colors on the floor and walls of the hall which roll or blend into one another and produce a very unique and beautiful color effect, some 30 of the rays being direct rays from the lamp through the lenses 37 and others being reflected rays from the reflector 15 and the reflecting surface of the frusto-conical portion 34 of the lamp body.
- 35 I claim as my invention:—
1. An illuminating device of the character described, comprising a revolving lamp body including a substantially conical lower portion having variegated lenses and a frusto-conical upper portion constituting a reflector in opposing relation to said lenses, a revolving light reflector including a source of light arranged within said lamp body for directing the light rays successively through 45 said lenses during the relative revolutions of the lamp body and the reflector, and means for transmitting motion to said revolvable parts.
  2. An illuminating device of the character 50 described, comprising a revolvable post, a revolving lamp body supported on said post to turn relatively thereto and including a conical lower portion composed of variegated lenses and a frusto-conical upper portion 55 forming an inner reflecting surface, a reflector including a source of light arranged within said lamp body opposite its lenses and fixed to said post to turn therewith, and means for turning the post and the lamp 60 body in opposite directions.
  3. An illuminating device of the character 65 described, comprising a revolvable post including a reflector support, a revolving lamp body applied to said post to turn relatively thereto and including a conical lower por-

tion having a plurality of lenses therein and a frusto-conical reflector portion in opposing relation to said conical portion, a source of light arranged within the lamp body movable with the post, a reflector for said light source adjustably mounted on said support for directing the rays of light through said lenses, and means for transmitting motion to the post and the lamp body.
